UNITED STATES PATENT OFFICE.

LEWIS PURYEAR, OF MEBANE, NORTH CAROLINA, ASSIGNOR OF TWO-THIRDS TO ELLIOTT J. McKNIGHT, OF GARDNER, MASSACHUSETTS, AND HENRY W. BASON, OF MEBANE, NORTH CAROLINA, AND ONE-THIRD TO LEVI G. McKNIGHT, OF GARDNER, MASSACHUSETTS.

FABRIC.

No. 922,811.

Specification of Letters Patent.

Patented May 25, 1909.

Application filed January 9, 1907. Serial No. 351,473.

To all whom it may concern:

Be it known that I, LEWIS PURYEAR, a citizen of the United States, residing at Mebane, in the county of Alamance and State of 5 North Carolina, have invented a new and useful Fabric, of which the following is a specification.

My invention relates to a new article of manufacture in the form of a fabric for chair-seats or backs, baby carriages, baskets and the like, formed from a substance which heretofore has been a waste material.

The chief objects of my invention are to produce a fabric of this character which will 15 be stronger, more easily worked, more durable, and also less expensive than has been the case heretofore, and to utilize for the reeds of the fabric, the leaf-stalks or mid-ribs of the saw palmetto which has been here- 20 tofore, so far as I am aware, a waste material.

Reference is to be had to the accompanying drawing, in which,

Figure 1 is a perspective view of the leaf- 25 stalk or mid-rib of a saw palmetto slit longitudinally to show how the reeds for the construction of the fabric are obtained. Fig. 2 shows one form of chair-seat made from the outside reeds thus obtained, and 30 Fig. 3 shows another form of fabric in which the piths or cores of the leaf-stalks are utilized as well as the outside reeds.

The main central rib or leaf-stalk of the saw palmetto heretofore has been regarded 35 practically as a waste material, and although it may have had some limited usefulness in certain arts, I believe it has not been used for the purpose of making fabrics. Now I have discovered that when properly dried and 40 treated, these main ribs may be utilized for the purpose of making fabrics for chair-seats and similar articles. In utilizing this material for the above mentioned purposes, the stalks are denuded of the leaflets and dried 45 and may, at the same time, be colored if desired. These stalks are of a general triangular shape in cross-section, and when dried they are split longitudinally near their outer surfaces into strands in the manner indicated 50 in Fig. 1, so as to provide a plurality of reeds having as their outer surface the exterior surface of the mid-ribs which is ordinarily of a somewhat smooth and finished appearance. These reeds are removed from the surface of

the outside of the leaf-stalk, leaving within a 55 substantially cylindrical shaped core or pith which also may be utilized. The reeds thus produced from the outside of the stem are trimmed to a substantially thin flat shape and woven in any desired way to produce the 60 fabric, and especially to produce chair-seats and backs etc. These reeds may be used alone in the manner indicated in Fig. 2, or they may be used in combination with the central core, a plurality of the cores being 65 placed longitudinally to constitute warp-reeds, and cross reeds or weft in both cases being formed of the split, thin, flat outer parts of the stems or mid-ribs as is indicated in Fig. 3, and they may be woven in any way 70 common with ratan. It is to be observed that by carrying out my method for the production of the outside and center reeds or the former alone, this waste material is utilized in such a way that it has great commercial 75 value. Furthermore, the material is light, durable and strong, and can be worked easily so that chair-seats and the like produced from it are of less weight and greater strength 80 and durability than those produced from some materials heretofore employed. Also the cost of manufacture is greatly reduced.

While I have illustrated and described certain forms in which my new material can be conveniently woven, it is to be understood that the same can be employed in any of the ordinary kinds of weaving for this and similar purposes. Therefore, I do not wish to be limited to the particular forms of weaving illustrated, but 85

What I do claim and desire to secure by Letters Patent is:—

1. As an article of manufacture a fabric formed entirely from reeds taken from the triangular stems or midribs of the leaves of the saw-palmetto, and the weft thereof consisting of such reeds made from the thin split, flat, outer skins of said triangular stems or mid-ribs reduced to a flat shape therefrom. 95

2. As an article of manufacture a fabric composed of longitudinal or warp reeds formed from the cylindrical pith or inner portion of the stem or mid-ribs of the saw palmetto, and cross reeds or weft strands 100 formed from the flat dried outer skins of said stems or mid-ribs. 105

3. The method of forming fabrics which

consists in drying palmetto stems or mid-
ribs, splitting the outside parts therefrom
leaving a substantially cylindrical center
piece, arranging a plurality of center pieces
5 side by side, and weaving the strips or reeds
taken from the outside portions of the stems
crosswise between said center pieces.

4. A method of making a fabric which con-
sists in removing the outer skins of the trian-
10 gular stems or mid-ribs of the leaves of the

saw-palmetto, reducing them to a flat shape,
drying them and weaving them as weft to
form a fabric.

In testimony whereof I have hereunto set
my hand, in the presence of two subscribing
15 witnesses.

LEWIS PURYEAR.
